PROCESS FOR THE PRODUCTION OF
MILK-PRODUCT POWDERS

Jacques Jean Ciboit, Paris, France, assignor to Societe Anonyme dite: Etablissements Laguillarre, Courbevoie, Hauts-de-Seine, France, a company of France

ABSTRACT OF THE DISCLOSURE

Production of a milk-product concentrate containing more than 45% dry solids, at a temperature greater than 45° C., by spray-drying said product to obtain a powder having a water content within the range of 4.5 to 7%, and followed by subjecting the resulting powder to a different secondary drying treatment so as to reduce its water content to approximately 3.5%.

This invention is directed to a process for the production of milk-product powders and also comprises, by way of novel industrial products, the powders which are obtained by means of said process. The invention is applicable especially, although not exclusively, to the production of powders of skimmed milk and the numerical values indicated in the following description relate to this particular product.

It is known that, in conventional spray-drying processes in which the starting material is a concentrate containing as a rule less than 45% of dry product and in which a dry powder containing less than 4% water is collected at the outlet of the spray chamber, the powders of the above type which are produced by these processes have satisfactory real solubility. On the other hand, these powders have a high content of occluded air and low density. The presence of a high proportion of occluded air gives rise to a disadvantage in that troublesome foam formation results when dissolving the powder for the purpose of reconstituting the milk. Furthermore, the low density of the said powders results in high total bulk of the containers in which they are packed. This last-mentioned disadvantage becomes particularly marked when the powder which is produced by a conventional spray-drying process is subjected to a later moistening treatment or so-called "instantaneization" treatment which is intended to increase its wettability, the known treatments of this type having the effect of reducing even further the density of the powder.

It is an admitted fact that a number of means are already known for increasing the density of a powder produced in a spray-drier and which consist either in increasing the percentage of dry material contained in the initial concentrate, or in increasing the viscosity of the said concentrate, or in reducing the speed of rotation of the disc in the case in which the spray atomization of the concentrate is effected by means of a centrifugal disc, or in reducing the pressure in the case of nozzles for spraying under pressure or with compressed air, or alternatively in modifying the inlet temperature of the drying air in the spray chamber. It is also known, however, that all the means referred to result in the production of powders which have poor real solubility if the drying in the spray-drier is continued until a water content below 4% is reached. If the spray drying process is carried out under these conditions, the powder retains poor real solubility even after an "instantaneization" treatment.

In addition, there have already been proposed a num-

ber of different processes for the production of skimmed-milk powder or lactoserum in which a concentrate containing a proportion of dry material which is higher than 45% is subjected to a spray-drying process so performed as to collect at the outlet of the drying chamber a powder having a high water content which can in certain cases be as high as 18%. These known processes, which aim to achieve without any external addition of water the stabilization of the product by the more or less complete crystallization of the lactose contained in amorphous form in the starting concentrate, in fact require the presence in the powder of a free moisture content which is higher than 8%. This is essential in order to ensure crystallization, which takes place in different cases either within the drying chamber itself or within a secondary apparatus in which the powder extracted from the drying chamber is maintained for a certain period of time in the presence of this moisture, the powder being subjected if desired to a subsequent complementary drying operation. Processes of this kind are attended by serious operating difficulties by reason of the sticky nature of powders which have such a high moisture content and which adhere strongly to the walls of the drying chamber, thereby calling for the utilization of mechanical or compressed-air means for the purpose of detaching them therefrom. In addition, this same moisture content has the effect of producing a certain degradation of the proteins, thereby resulting in a reduction in the real solubility of the powder. It has further been observed that powders in which the lactose has crystallized do not lend themselves to a subsequent instantaneization treatment as readily as normal spray-dried powders, in particular when it is desired to obtain a powder in the form of granules.

The process according to the present invention has for its object to eliminate the various drawbacks which have just been outlined by making it possible to obtain milk-product powders which have in particular the following combination of properties:

- 40 (1) Contrary to the powders produced by conventional spray-drying process, the lactose contained in the powders produced according to the invention is practically unmodified or, in other words, has remained in an amorphous form;
- 45 (2) The said powders have a high density;
- (3) They contain a small proportion of occluded air;
- (4) They have excellent real solubility.

To this end, the process in accordance with the invention consists in principle in subjecting to a spray-drying process a concentrate containing a proportion of dry material which is higher than 45% and preferably between 50 and 55% and having a temperature which is higher than 45° C. and preferably in the vicinity of 60 to 65° C., by effecting the drying in the spray-drier until a powder is obtained having a water content within the range of 4.5 to 7% and preferably between 4.5 and 6%, and in then subjecting the powder thus obtained to a secondary drying operation so as to reduce its water content to approximately 3.5%.

Apart from the characteristic properties with which the powder is endowed as indicated earlier, it should be pointed out that, by operating within the specified limits of water content at the outlet of the drying chamber, the process in accordance with the invention is not liable to result in the formation of any deposit on the chamber walls, thus considerably facilitating operating conditions with a view to achieving a continuous and steady manufacturing process on an industrial scale.

In the practical application of the invention, the spray-drying stage will preferably be effected in a drying tower fitted with a spraying device consisting either of pressure

nozzles or compressed-air nozzles. Good results can sometimes also be obtained by making use of a spray device with centrifugal disc.

The secondary drying of the powder produced in the spray-drier is preferably carried out immediately after separation of the powder from the drying air, and can be carried out by any suitable means, for example in a compressed-air system which is supplied with hot air or on a drying table.

In all cases, the powder which has been subjected to the secondary drying process can be subjected if necessary to a bolting operation or to the action of a cyclone selector for the purpose of separating the finest particles from the said powder.

In all cases also, the powder which has been subjected to the secondary drying treatment can undergo a cooling process.

The comparative table given below indicates by way of nonlimitative example the results obtained in the production of a skimmed milk powder, on the one hand by means of a conventional spray-drying process and, on the other hand, by means of the process according to the invention by making use in both cases of different types of spraying devices.

NORMAL TREATMENT WITHOUT REMOISTENING OF THE POWDER

	Pressure spraying nozzles		Compressed-air spraying nozzles		Centrifugal disc	
	Conventional spraying treatment	Treatment according to the invention	Conventional spraying treatment	Treatment according to the invention	Conventional spraying treatment	Treatment according to the invention
Concentration prior to spraying	43-44%	48 to 56%	40-42%	46 to 48%	45-47%	50 to 75%
Temperature of the concentrate	45° C.	60° C.	45° C.	60° C.	45° C.	60° C.
Intermediate moisture content of the powder	5.5%	5.5%	5.5%	5.5%	5.5%	5.5%
Final moisture content	3.5%	3.5%	3.5%	3.5%	3.5%	3.5%
Commercial density	0.6	0.7	0.6	0.7	0.45	0.55
Occluded air	15 cm. ³ /100 g.	8 cm. ³ /100 g.	16 cm. ³ /100 g.	8 cm. ³ /100 g.	35 to 50 cm. ³ /100 g.	20 to 30 cm. ³ /100 g.
Real solubility	Good	Very good	Good	Good	Good	Good

In the application of the process according to the invention, it is possible in all cases to increase the proportions of dry material contained in the starting concentrate as indicated in the above table so as to bring them, for example, above 55%, provided that the evaporator which is employed for the preparation of this concentrate permits the possibility of obtaining such a degree of concentration in normal industrial operation. It is in that case also necessary to increase the moisture content of the powder at the outlet of the spray-drier to approximately 6-6.5%.

Furthermore, as has been mentioned earlier, all the numerical values which have been specified in the foregoing have been given in the case of skimmed milk. However, it should be made clear that the invention also applies to the treatment of other milk products and in particular to milk having a high fat content (whole milk or enriched milk) and results in a similar improvement in the qualities of the powders which are finally obtained, although this last-mentioned application has higher concentrations of starting concentrates.

It must finally be understood that the present invention also includes within its scope any alternative form of execution of the process described above, in which the increase in concentration of the starting concentrate as a means for increasing the density of the final product is replaced by one or a number of other known means for achieving the same result and which have been mentioned earlier (increase in the viscosity of the concentrate, reduction of the speed of the spraying disc or of the pressure of the spraying nozzles, modification of the inlet tempera-

ture of the drying air in the spray-drier), while at the same time retaining the other characteristic features of the invention (temperature of injection of the concentrate higher than 45° C. and preferably in the vicinity of 60-65° C., water content of the powder at the outlet of the drying chamber within the range of 4.5 to 7%, and secondary drying of the powder). However, it would appear that, among the known means for increasing the density of the powder, the increase in concentration of the starting concentrate constitutes the most advantageous factor in the practical application of the invention since it additionally results in a substantial reduction in the quantity of water which is evaporated in the spray-drier and consequently a very considerable economy in total consumption of steam which is necessary for the entire process.

What I claim is:

1. Process for the production of milk-product powders, comprising the steps of providing a starting milk-product concentrate containing a proportion of dry material which is greater than 45% and having a temperature which is greater than 45° C., subjecting the starting milk-product concentrate to a spray-drying process by effecting the drying with drying air in the spray-drier until a powder is obtained having a water content within the range of

4.5 to 7%, and separating the powder from the drying air and then subjecting the powder thus obtained and having a water content within the range of 4.5 to 7% directly to a different secondary drying process for a period of time so as to reduce its water content to approximately 3.5%.

2. Process for the production of milk-product powders as defined in claim 1, wherein the starting milk-product concentrate contains from 50 to 55% dry solids and is at a temperature within the range of 60 to 65° C. when it is fed into the spray drier, and wherein the powder obtained from the spray-drying process has a water content within the range of 4.5 to 6%.

3. Process in accordance with claim 2, further including the steps of subjecting the powder from the secondary drying process to a separation operation so as to separate the finest particles therefrom, and then reintroducing the separated fine particles into the spray-drier.
